YARN WINDING MECHANISM

Robert A. Leeson, Boston, Mass., assignor to Universal Winding Company, Boston, Mass., a corporation of Massachusetts

Application March 6, 1933, Serial No. 659,620

2 Claims. (CL 242—43)

This invention relates to means for producing a yarn package, and particularly to means for traversing the yarn lengthwise of the package to deposit it thereon in helical coils.

5 The object of the invention is to produce a yarn package of the most useful and practical shape, which shall be drum wound, or wound from a Reece roll, and to produce a drum or Reece roll capable of winding such a package.

10 The invention herein specifically comprises a modification of and improvement on Reece Patent No. 1,749,355, granted March 4, 1930, wherein traversing means for winding machines is disclosed which comprises a cylindrical roll or drum, having a surface groove in the form of opposite crossing helices extending the length of the roll, the roll being in contact or approximate contact with the yarn package, and the yarn is guided onto the package by means of the guiding groove.

15 Briefly, my invention consists in providing the cylinder of the Reece roll or of any winding drum with a concaved surface, inclining the axis of the cop-tube or yarn-receiver at an angle to the axis of the receiver roll, in horizontal projection, whereby there is a frictional contact between the entire peripheral surfaces of the roll and yarn package as each revolves. In this way a yarn package of the ideal shape is produced on the Reece roll.

20 While the invention is illustrated and spoken of as an improvement on the Reece roll, it is not so limited in its application, but is applicable to any drum winder, even though the yarn be guided onto the package by means of the old reciprocating traversing arm.

25 Other objects and advantages of this invention will appear in the following description and appended claims, reference being had to the accompanying drawing forming a part of this specification wherein like reference characters designate corresponding parts in the several views.

In the drawing:

Fig. 1 is a front elevational view of a Reece roll, modified to embody my invention.

30 Fig. 2 is a front elevational view of a yarn package produced by my modified Reece roll with its parts diagrammatically indicated thereon, and the bulging ridge on the ends of an ordinary package indicated in dotted lines.

35 Fig. 3 is a front elevational view of my modified Reece roll in contact with the yarn package; and

40 Fig. 4 is a plan view showing the respective axes of rotation of the roll and yarn package in horizontal projection.

Before explaining in detail the present invention it is to be understood that the invention is not limited in its application to the details of construction and arrangement of parts illustrated in the accompanying drawing, since the invention is capable of other embodiments and of being practiced or carried out in various ways. Also it is to be understood that the phraseology or terminology employed herein is for the purpose of description and not of limitation; and it is not intended to limit the invention claimed herein beyond the requirements of the prior art.

45 In the drawing the grooved traverse roll or Reece roll which serves as a means for guiding the yarn onto the package is indicated at 10. The 50 yarn package may be driven from a driving roll or drum not shown, or it may be driven directly from the Reece roll 10 as indicated in Fig. 3. The roll 10 is similar in all respects to the Reece roll of the Reece Patent No. 1,749,355, except that 55 instead of being a true cylinder, its surfaces are concaved as shown in Fig. 1. As in the Reece roll, the groove in the periphery of the roll 10 continues from one end to the other and back again in the reverse direction, but for convenience 60 of description that part of the groove which extends in one direction will hereafter be referred to as one groove 11 and the other part extending in the opposite direction as another groove 12. The two 65 grooves 11 and 12 may be of uniform length and pitch, and with any desired number of convolutions or turns about the axis of the traverse roll 10. For winding the frusto-conical shaped package and to insure an even distribution of yarn 70 on the package, the grooves or helices are constructed of variable pitch, with the steeper pitch, and consequently the turns farther apart, at the 75 end adjacent the small end of the yarn package. As shown in Figs. 1 and 3, the pitch of the grooves 80 is arranged to distribute more yarn on the large end of the package and less on the small end, thus 85 making an evenly wound cone-shaped package. As shown, each groove makes four turns or revolutions from one end to the other, and there are 90 consequently three crossing points on one side 95 of the roll and four on the reverse side, as shown in Fig. 1. With the grooves in the roll arranged as shown herein the yarn being guided for traverse therein will be caused to make four turns or convolutions around the surface of the cop-tube or 100 yarn receiver T at the start of the winding, assuming that the diameters are the same and that the receiver is drawn at the same rate of speed as the roll. But as the yarn mass increases in 105 diameter the cop or package 15 will be rotated 110

115

at a gradually diminishing speed and consequently the strand will be laid with a correspondingly less number of turns in its traverse from one end of the package to the other.

5 The grooves 11 and 12 in the surface of the traverse roll 18 may be of suitable width to accommodate varying thicknesses of yarn. The two grooves 11 and 12 are of substantially uniform depth throughout a portion of their extent, but at the points where they intersect the bottom profile of one groove is raised above the other, as shown in the Reece patent in accordance with the direction in which the strand travels in the groove. In other words one groove is less in depth 10 and the other groove is deeper to prevent the strand from being diverted at the crossover in the groove in which it is travelling in one direction to the groove extending in the opposite direction. As shown in Fig. 1, the grooves 11 and 12 are 15 bevelled off or chamfered on their sides at points beyond the crossovers, these chamfered portions being designated generally by the reference character 14. When the strand travelling in one groove meets the other groove at the crossover there would be a tendency, if not so chamfered, 20 for it to catch on the point projecting toward the crossover so that it might be diverted into the groove extending in the opposite direction and thus fail to be traversed throughout the whole 25 length of one groove before being reversed to return in the other groove. To prevent such diversion of the strand at points at the crossovers the grooves are chamfered or bevelled off as at 14.

30 For a more complete disclosure and description 35 of the method and operation of the Reece roll, reference is made to the drawing and specification of the Reece Patent No. 1,749,355, aforesaid.

35 Fig. 1 of the Reece patent shows a front elevation of the traversing roll and cop-tube or yarn receiver T with their surfaces in contact, and 40 Fig. 2 is a plan view of the same showing that the axes of rotation of roll and tube are in a common oblique plane but at an angle to each other in that plane. This arrangement of a cone-shaped 45 tube and yarn package, however, in which the two axes of rotation are at an angle to each other in their plane is not essential to the operation of the Reece roll, because a true cylindrical package can be wound as well, in which the respective axes 50 of rotation are parallel in their common plane. By experience it was found that in winding from this position of roll and tube, there was a distortion or tension on the yarn at the apex end of the tube which resulted in a poorly formed and defective package. This difficulty was overcome by 55 tilting the tube outwardly in a horizontal plane on an axis substantially central of tube and roll (when looking at the machine from the front as in Fig. 1) and displacing the axes of rotation of roll and tube from their common oblique plane and making them at an angle to each other in horizontal projection. In this position the ends 60 of the tube were no longer in peripheral contact with the ends of the roll and there was a piling up of yarn to produce an annular ridge 16 on the ends of the package, as shown in dotted lines in Fig. 2 herein, producing a concave-surfaced package. This package proved most unsatisfactory, as in drawing the yarn off the top, it would 65 rub or catch against the ridge or bulge 16 at the top of the package, interfering with unwinding, and causing weakening or breakage of the yarn.

I have overcome these difficulties by means of my invention which consists in concaving the surface of the Reece roll from end to end (as shown in Fig. 1 herein). Thus with the axes of rotation of roll and tube inclined at an angle to each other in horizontal projection, there is a frictional contact between the entire peripheral surfaces of roll and package as each revolves. Because of this frictional contact the yarn is wound evenly on the package producing a true 10 frustro-conical surface from top to bottom of the package, and without the bulging ends 16 which interfere with unwinding. And because the axes of rotation of roll and tube are not parallel in the vertical plane, there is no distortion of the 15 yarn in winding on the apex end of the package. It is obvious that the degree or radius of concavity on the Reece roll can be varied as desired according to the length of the yarn package and the angle of inclination of the yarn tube toward 20 the roll in a vertical plane. As shown in Fig. 1, the most satisfactorily shaped package is frustro-conical, with the bottom or under surface tapering like a saucer, and the top surface concaved, but the mechanism for forming the top and bottom surfaces is well known and forms no part of my invention.

The yarn package can be made convex or barrel-shaped on the sides, if desired, merely by changing the degree or radius of concavity of 30 the roll. Such a package is more satisfactory for some purposes than the true conical-shaped package. A deeper concavity on the roll for instance, with the angle of inclination of yarn tube and roll and their respective lengths kept constant, would produce a frictional contact chiefly at the ends of the yarn package and there would be a piling up of yarn in the middle of the package, giving it a convex or barrel shape.

The shape of the yarn package is highly im- 40 portant in the textile industry and by means of 45 my invention I have enabled a yarn package of the ideal shape to be produced on the more effective Reece roll. The advantages are, first, that the package unwinds better, since in drawing 50 the yarn off the surface of the cone into a knitting machine, for instance, there is no chance for the yarn to wear or catch against any ridge on the end of the cone, and second, the package transports better, since in transportation the 55 friction of the cones against each other is distributed over the entire surface instead of confined to the ends, and this prevents wear and weakening of the yarn strands.

I claim:

1. In a winding machine a concaved cylindrical rotating element having a strand receiving and guiding groove on its peripheral surface, and a yarn receiver mounted for peripheral contact with said rotating element, the axes of rotation of said yarn receiver and rotating element being inclined at an angle in horizontal projection.

2. In a winding machine a concaved cylindrical rotating element having a strand receiving and guiding groove on its peripheral surface consisting of crossing and connecting helices, and a yarn receiver mounted for peripheral contact with said rotating element, the axes of rotation of said yarn receiver and rotating element being inclined at an angle in horizontal projection.

ROBERT A. LEESON.
